SAFETY DEVICE

Emile Schaefer, Geneva, Switzerland

Application July 25, 1938, Serial No. 221,206
In Switzerland July 27, 1937

1 Claim. (CL 200—52)

The present invention relates to an improved electrical safety device for motor vehicles and more particularly to an improved automatic circuit breaker for use in ignition circuits of said vehicles and adapted to automatically break the electrical circuit upon turning over of the vehicle or when the vehicle is tipped unduly or collided with an obstacle.

It is an object of the invention to provide a circuit breaker so constructed as to form a hermetically closed, evacuated exterior vessel protecting the fluid conductor from oxidation and permitting it to escape more quickly when the breaker is tilted sufficiently or inverted.

A further object of the invention is to provide a breaker which can be re-set to operating condition simply by tilting the whole device upside down in a determined manner and, hence, turning it further into its normal position without necessitating parts of the breaker to be substantially removed or operated.

A still further object of the invention is to afford a permanent controlling of the state of the breaker as well as a controlling of its re-setting action.

According to these objects, the invention is concerned with the provision of a breaker wherein the evacuated exterior vessel is in form of a bulb divided into an upper and a lower chamber by means of a transverse partition, and wherein the fluid conductor and the contacts are disposed in an interior vessel mounted within said lower chamber and carrying a plug through which it communicates, on the one hand, with the lower chamber of the exterior vessel by means of perforations provided in said plug, and, on the other hand, with the upper chamber of the exterior vessel by means of a tube extending between said plug and the transverse partition.

The drawing illustrates:

Figure 1 is a vertical section along the center line of the safety device showing a preferred embodiment of the invention.

Figure 2 is a section along the line 2—2 of Figure 1.

Figures 3, 4 and 5 show the way how the device must be put back again into working condition.

The safety device represented in the drawing resembles outwardly to a bulb and comprises a socket 1 wherein a hermetically closed vessel 2 is fixed which is divided by a partition 3 into two superposed chambers 4 and 5 communicated through the opening 6 in the partition 3. In the lower chamber of the vessel 2 is disposed a second vessel 7 containing mercury 8 and two contact

members 9 electrically connected by said mercury and penetrating through the bottom 10 of the vessel 7 and the socket 1, and forming outside two plugs 11 which can be put into a plug bush inserted in the ignition circuit of a motor vehicle.

Inside the vessel 7 above the level of the mercury is disposed a stopper formed by a plug 12 constituted by two disks perforated along their rims in a manner that the perforation 13 of one disk is staggered with respect to the perforation 14 of the other disk. In this way the mercury cannot leap out of the vessel 7 under the action of trepidations or shocks to which the vehicle is subjected, whereas, when owing to an accident the vehicle is overturning that the safety device 15 comes into horizontal or upside down position, the mercury can freely escape through the perforations 13 and 14 into the vessel 2, whereby the ignition circuit of the motor is cut off.

The chamber 5 of the vessel 2 is in communication with the interior of the vessel 7 by a tube 15. We have seen that owing to the overturning of the vehicle in an accident, the mercury can leave the contact members 9 and escape into the vessel 2. This escape of the mercury could also happen 20 by handling the device or when storing it. For this reason the vessel 2 is divided in two superposed chambers 4 and 5 permitting to put the safety device back again into working condition. Indeed, if the device is overturning (Fig. 3), the 30 mercury is running into vessel 2. If this turning is continued according to the arrow in Fig. 3 into the upside down position (Fig. 4) the mercury is passing through the opening 6 of the partition 3 into the chamber 5. Afterwards the device 35 must only be brought back according to the arrows in Fig. 4 into the normal, vertical position (Fig. 5). The mercury is in the chamber 5 and is then running through the tube 15 into the vessel 7 containing the contact members 9. An 40 edge 16 round the opening 6 prevents mercury from escaping back into the chamber 4. The safety device is thus again in working condition.

It will be preferable to prevent oxydation of the mercury by evacuating the vessel 2. A 45 safety device can not only be disposed in the ignition circuit of the motor but as well in other electrical circuits of the motor vehicle, for instance, that of the head-lights or of the hooter, stopping also those apparatus in case of an 50 accident.

I claim:

A circuit breaker of the character described comprising a hermetically closed exterior vessel adapted to be evacuated, a transverse partition 55

mounted within said exterior vessel and dividing the same into an upper and a lower chamber, said partition being provided with an opening through which said chambers communicate with each other, an interior vessel mounted within the lower chamber and containing the mercury, said interior vessel carrying a plug through which it communicates, on the one hand, with the lower chamber of the exterior vessel by means of perforations provided in said plug, and, on the other hand, with the upper chamber of the exterior vessel by means of a tube extending between said plug and the transverse partition, said plug be-

ing adapted to prevent undue splashing or escaping of the mercury when the vehicle is in motion while permitting the mercury to flow out into the exterior vessel thereby breaking the connection between the contacts when the breaker is substantially inverted, whereby, in order to re-set the breaker, the mercury spread in the exterior vessel can be collected in the upper chamber and led back through said tube into the interior vessel by tilting the breaker upside down in a determined manner, and, hence, turning it further into its normal position.

EMILE SCHAEER.
